FELICIE EUGENIE AMELIE WANPOUILLE BERGAUD, OF PARIS, FRANCE

CASE FOR LIPSTICKS

Application filed July 9, 1931, Serial No. 549,719, and in France July 30, 1930.

There are already on the market numerous cases for lipsticks in which the lipstick is released from the case (holder) by sliding. This arrangement, however, presents certain inconveniences: For example, the movable cap which completes and closes the case must be removed whenever one wants to use the lipstick and on account of this it can easily be lost.

10 In the improved case, which is the subject matter of the invention, the lipstick is released from the case also by sliding, but the closing member of the case is integral with the said case and is constituted by two 15 undulated members, guided by slides and sliding in the case and meeting at the end of the case; these undulated members resemble, in appearance and operation, the rolling tops of so-called American roll top desks.

20 The removing of these undulated members or curtains (shutters) can be obtained in any desired manner, for example by acting on the heel or base of the case which 25 is movable with respect to the body of the case and is fixed or connected to the said shutters.

20 In an embodiment of this invention there are provided three lockings by means of 30 slots, spur and small plate, having the following purpose:

35 1. To prevent that the lipstick can be displaced or moved in the case when the shutters are closed and therefore to prevent that the end of the lipstick crushes against the said shutters.

40 2. To hold fast the shutters in the open position when the lipstick is out, in order to avoid that the latter is cut or sheared by the said shutters.

45 3. To prevent any displacement of the lipstick during the closing of the shutters which would produce the same inconvenient feature, i. e. the cutting of the lipstick by the shutters.

50 In another manner of realization of the invention one of the ends of each one of the two shutters is connected with the base of the lipstick in such a manner that by the opening or closing of the shutters the lip-

stick is caused either to come out or go into the case.

The shutters can be operated directly by hand or the base of the lipstick can be provided with a push button serving for its 55 operation.

The following specification, together with the attached drawings, given by way of example, show clearly in what manner the invention can be realized.

60 Figs. 1, 2 and 3 are total views of the case which is the subject matter of the invention, in its different phases of operation.

Fig. 4 is a plan view of Fig. 3.

65 Fig. 5 is a vertical section, on a large scale, of the case in its closed position.

Fig. 6 is a cross-section according to the plane along the line VI—VI of Fig. 5.

70 Fig. 7 is an outside plan view corresponding to Fig. 6.

Fig. 8 is a similar view, the heel or lower part of the case being displaced in order to cause the opening of the movable shutters.

75 Fig. 9 shows the case with the lipstick entirely released from the case.

Fig. 10 is a detailed view of the case proper.

Fig. 11 is a detailed view of the shutters and their extension.

80 Fig. 12 is a detailed view of the lipstick.

Fig. 13 shows the small locking plate.

85 Fig. 14 is an elevation with partial cross-section showing one mode of realization of the invention.

Fig. 15 is a section along the line XV—XV of Fig. 14.

90 Fig. 16 is a detailed view of one of the closing shutters.

Fig. 17 is a view similar to Fig. 15, the lipstick being entirely released from the case.

95 As one can note from the drawings, the case is constituted by a body 1 of an elongated shape and of rectangular cross-section, the ogive pointed end 2 of which (Fig. 4) is notched (cut) at 3, (Fig. 2), the recess 3, in non-operating position, being covered by the shutters 4; the latter consisting of thin and undulated metal sheets forming the extension of the opposed faces of a tube 5 100

engaging in the body 1 of the case, in such a manner that they can slide freely.

To the end of the tube 5 and by means of screws 5^a, there is fixed a bottom 10, having the same section as the body of the case, so that when in closed position (Fig. 1), this bottom constitutes the heel or base of the case.

One can understand that the opening and closing of the shutters is very simple, as can be noted from Figs. 1 and 2. It is done by holding with one hand the body 1 of the case and drawing or pushing with the other hand at the bottom 10.

15 In their sliding motion the shutters 4 are guided by the edges 9 of the body 1 of the case and by the inclines 11 (Fig. 6) which extend along the pointed end of the body of the case.

20 The shutters 4 being open, one can, by means of the mechanism which is described below, cause the lipstick to come out, as shown in Figs. 3 and 4.

Inside of the case there is arranged the 25 lipstick 6, the sliding of which is caused by the push button 7, the shank of which slides at the same time in a slot 8 of the body 1 of the case, which slot is oblique (inclined) with respect to the longitudinal axis of the 30 case, as can be seen from Figs. 7 and 8, and in a slot 15, having the same incline, of a tube 5.

The lipstick 6 is carried by a cap 12, which moves freely in the tube 5. This cap 12 is 35 provided with a cross slot 13 (Fig. 12) in which passes the shank 14 of the push button 7, which shank passes likewise through the slot 15^a, 15^b, 15 of tube 5 and in the slot 8, 8 of the body 1 of the case.

40 Finally the shank 14 passes likewise in a notch 17 provided on a small sliding lock plate 18 (Fig. 13). This small lock plate 18 is provided with a spur 19 which slides in the end 8^a of the slot 8 and with a spur 20, sliding both in a cross slot 21 provided on the body 1 of the case (Fig. 10) and in the slot 16 of the tube 5.

In the non-operating position the shank 14 of the push button 7 traverses the body 1 of the case in the part 8^a of the slot 8.

45 The operation of the case comprises the following operations:

(a) Opening of the shutters 4 (Figs. 1 and 7); with one hand draw the bottom 10 of the case in the direction of the arrow F, while holding the body of the case (Figs. 2 and 8) with the other hand. In its motion the tube 5, which is integral with the bottom 10, is guided by the shank 14 and spur 20 which remain stationary and along which there slide the slots 15^a and 16 until the said shank and spur strike against the bottoms of the slots 15^b, 16^b (Fig. 8).

The shutters 4 having slid along the edges 50 9, have disappeared against the inner wall

of the body 1, of the case in such a manner that the front end of the case is opened (Figs. 2 and 8) and one can push the lipstick 6 in order to make it come out of the case.

70 During this opening operation of the shutters, the lipstick 6 cannot be displaced longitudinally on account of the fact that the shank 14 is engaged in the transverse part 8 of the slot 8 (Fig. 10). Therefore 75 the lipstick 6 has been locked in position.

(b) Displacement of the lipstick.

The lipstick 6 is displaced transversely in the direction of the arrow F¹, Fig. 8, in order to bring its shank 14 to the end of the inclined slot 8 which unlocks the cap 12 of the lipstick 6. At the same time the shank 14, engaged in the notch 17 of plate 18 (Fig. 13) takes along the latter transversely and the spur 20 of the said small plate engages in the transverse slot 16^b of the tube 5 (Fig. 11) which prevents the displacement of the bottom 10 which is in this way locked in the opening position.

80 At this moment the lipstick 6 can be freely moved by pushing the button 7, the shank 14 of which slides both in the slot 8 and in the slot 15, which at the time of the opening of the shutters, has come in the position under the slot 8 (Figs. 8 and 9); on this last mentioned figure the lipstick has been shown completely released from the case, but it is obvious that at the time of its use, one 85 will only release the necessary quantity in order not to risk the breaking of it.

90 After using the lipstick it suffices, in order to have it go back into the case, to slide the push button 7 in the slot 8 in order to bring same up to part 8^a. During this displacement the shutters cannot close, because, as 95 has been noted previously, any longitudinal displacement of the tube 5 is prevented.

100 When the lipstick has completely entered the case, the tube 5 is unlocked by transversely displacing the button 7 in the part 8^a of the slot 8 in the direction opposite to that of arrow F¹. At this moment the shank 14 is engaged in the part 8^a; the lipstick can no longer be displaced with respect to the body 1 of the case and in this condition, 110 if one pushes in the bottom 10 against the body 1 of the case, which produces the closing of the shutters 4, the lipstick remains immovable and there is no risk of its crushing against the shutters.

115 It must be stated that by reason of the inclined position of the slots 8 and 15, they do not superimpose when the case is closed (Fig. 7) and in this way it is prevented that any dust can penetrate into the case.

120 Furthermore, when the two slots 8 and 15 are superposed (Fig. 8), the inclined position assures a certain wedging of the shank 14 by friction of the shank in the slot, which maintains the lipstick in the protruding po- 125

sition (Fig. 9) and prevents its returning into the case under the pressure exercised against the lips.

One could finally contemplate that the 5 displacement of the shutter operates directly the pushing out of the lipstick.

For this purpose the shutters could be 10 prolonged up to the base of the tube forming half a circle at the end and would come to rest against the bottom of the cap 12 which maintains the stick, in such a position 15 that by lowering the upper part of the shutters by hand or by any other suitable operation, in order to release the opening, the lower part would come up and cause the lipstick to project from the case.

In the other manner of realization shown 20 in Figs. 15-17, the cap 12 carrying the lipstick 6 is provided with two buttons 22 passing through the body 1 of the case in a slot 23.

The undulated shutters 24 and 25 are 25 provided with extensions 26 and 27 (out of true with respect to the axis of the shutters) which are connected with the base 12 at 26^a and 27^a.

One can clearly note that any displacement of the lipstick obtained by letting the shanks of the push buttons 22 slide in the 30 slot 23 in order to bring them from the position shown in Fig. 16 to the position shown in Fig. 17, brings about directly a carrying along movement, in the direction inverse to that of the shutters 24 and 25 which 35 are brought back into the body 1 of the case, and uncovers the opening 28 provided in the point of the case in such a manner that the lipstick can leave the case freely.

By bringing back the buttons 22 to the 40 rear, the lipstick is caused to enter the case and at the same time there is brought about the closing of the case by the shutters 24 and 25.

The shutters are guided in their movement 45 by the inclined parts 11^a and 11^b.

It is clearly evident that changes in detail can be made in the embodiments or realizations described above without in this 50 way going beyond the scope of this invention.

What I claim is:

1. A case for lipsticks comprising a body, a tube slidable therein and projecting through the rear end of the body, and coacting 55 shutters forming front extensions of the tube for opening and closing the front end of the body as the tube is moved rearwardly and forwardly respectively.

2. A case for lipsticks comprising a body, 60 a tube slidable therein and projecting through the rear end of the body, coacting shutters forming front extensions of the tube for opening and closing the front end of the body as the tube is moved rearwardly and forwardly respectively, and guides

for said shutters at the front end of the body.

3. A case for lipsticks comprising a body, a tube slidable therein and projecting through the rear end of the body, coacting 70 shutters forming front extensions of the tube for opening and closing the front end of the body, and a lipstick holder slidable in the tube.

4. A case for lipsticks comprising a body, a tube slidable therein and projecting through the rear end of the body, coacting 75 shutters forming front extensions of the tube for opening and closing the front end of the body, a lipstick holder slidable in the tube, and means for automatically locking the lipstick holder against movement during the opening and closing movement of the shutters.

5. A case for lipsticks comprising a body, a tube slidable therein and projecting through the rear end of the body, coacting 80 shutters forming front extensions of the tube for opening and closing the front end of the body, a lipstick holder slidable in the tube, and coacting means between the body, 85 tube and lipstick holder for locking the lipstick holder against movement during the opening and closing movement of the shutters.

6. A case for lipsticks comprising a body, a tube slidable therein and projecting through the rear end of the body, coacting 90 shutters forming front extensions of the tube for opening and closing the front end of the body, a lipstick holder slidable in the tube, means for sliding the lipstick holder, and coacting means between the body, the tube 95 and the lipstick holder for locking the lipstick holder in its extended and retracted 100 positions.

7. A case for lipsticks comprising a body, a tube slidable therein and projecting through the rear end of the body, coacting 105 shutters forming front extensions of the tube for opening and closing the front end of the body, a lipstick holder slidable in the tube, and coacting means between the body, the tube and the lipstick holder for causing opposite relative movements of the tube and 110 lipstick holder whereby the opening and closing of the shutters will cause the forward and rearward movement of the lipstick holder and vice versa.

In testimony, that I claim the foregoing 115 as my invention, I have signed my name this 20th day of June, 1931.

FÉLICIE EUGENIE AMELIE WANPOUILLE BERGAUD.
